UNITED STATES PATENT OFFICE.

ERNEST H. JACOBS, OF CHICAGO, ILLINOIS, ASSIGNOR TO ELECTRICAL ENGINEERS' EQUIPMENT COMPANY, OF CHICAGO, ILLINOIS, A CORPORATION OF ILLINOIS.

LOW-VOLTAGE RELEASE-SWITCH.

1,380,386.

Specification of Letters Patent. Patented June 7, 1921.

Application filed August 8, 1918. Serial No. 248,971.

To all whom it may concern:

Be it known that I, ERNEST H. JACOBS, a citizen of the United States, residing at Chicago, in the county of Cook and State of Illinois, have invented a certain new and useful Improvement in Low-Voltage Release-Switches, of which the following is a full, clear, concise, and exact description, reference being had to the accompanying drawings, forming a part of this specification.

My invention relates to low voltage release switches.

Continuity of service is one of the requirements of electrical service. Generally in modern distributing systems the continuity of service is remarkably high. The desirability of continuity is apparent to the consumer even in such a simple case as a pure lighting load. The really serious results of discontinuity are not found in a pure lighting load as current may be turned off and on without damage. However, in the case of a power load a different condition prevails. If the current goes off a power load long enough to cause slowing down of the motors or other rotary apparatus and then is thrown on suddenly, the rotary apparatus may not be able to pick up its speed under load and may be damaged. Furthermore the large rush of current often injures the line or protective device and causes serious consequences.

It has heretofore been proposed to employ switches for automatically interrupting the supply circuit when the voltage falls below a predetermined value and such devices are now in common use. My present invention provides an improved form of low voltage release switch of the above described class.

My invention also provides means for automatically switching the consumption circuit upon another supply circuit when voltage fails on the primary supply circuit. Thus the consumption circuit is subject to a minimum of discontinuity as the action of the switch is substantially instantaneous in transferring the consumption circuit from one source to a secondary source.

My invention further provides an alarm controlled by shifting of the switch. A further improvement resides in the releasing mechanism for the switch and the means for resetting the switch.

Other subsidiary objects will be apparent from the following detailed description.

Figure 1 is a front elevation of a switch constructed in accordance with my invention;

Fig. 2 is a side elevational view of the same;

Fig. 3 is a detail view of the latching mechanism taken on line 3—3 of Fig. 2;

Fig. 4 is a detail view taken on line 4—4 of Fig. 1.

Figs. 5 and 6 are detail fragmentary views of the cam mechanism employed.

The movable part of the switch comprises the pairs of blades 1, 2 and 3 which are of the floating blade type, and which are clamped or pivoted in the center to the stationary lugs 4 by means of the bolts 5. The lugs 4 are secured to a suitable base board or panel 6 which may be of slate, marble or the like, as is usually employed in switchboard construction. The respective blades of each pair of blades are held together at their extremities by the bolts 8 and 9 and the spring washers 10 and 11. A suitable handle 12 is provided with extensions or tongues 13 which serve as spacers for the upper ends of the pairs of blades 1, 2 and 3. These tongues 13 serve as spacers and prevent the respective blades from being drawn too closely together by the bolts 8 and washers 10. To make the handle sure and easy to grip, a rod 14 is bolted to the supports 15 and 16 which are mounted on a rectangular block 17, all of which are made of insulated material. The lugs or terminals 18 which are mounted upon the base 6 and connected to the generator line, engages the blades at the upper ends thereof. The bolts 8 and 9 serve to guide the lugs when engaging the blades, thus affording proper alinement.

If the line potential of the generator should fall below a predetermined point the armature of the electro-magnet is released and the spring automatically throws the switch blades to the alternative contacts which are connected to some other source of supply, such as a storage battery. This electromagnet comprises an armature 25 and a magnet 20. The magnet 20 is mounted by the screws 21 on a Y shaped support 22 which is fastened by means of bolts 23 to the base 6. The armature 25 is mounted on a lever 27 having a toggle movement. The link 27 connected at one end to the armature 25, is fulcrumed at its center to lug 26 projecting from the casing of the magnet. 110

The other end of this link 27 is connected to a link 28 by the bolt 29 which has a limited free vertical movement in the slot 30. An extending arm 31 passes through an 5 aperture 32 of the base 6, and has its end formed into a hook 33.

This arm is pivoted by the pin 34 to the extending lug 35 serving as a fulcrum for the same, the other end of which is fastened 10 to the link 28, thus completing a toggle movement when the lever 27 is operated. The lugs 35 are formed integral with a bushing 36 which is fitted into the aperture 32 to serve as a protecting member to the 15 insulated mounting and is threaded at its other end to a collar 37, making it impossible to move out of position. A lever 38 with a finger 39 at one end is also pivoted to the lug 35 and passes through the aperture 32, having its opposite end 42 turned 20 upward so that it will bear upon the under surface of the link 27.

A block is mounted on the insulated bar 17 having cams 40 and 41 projecting therefrom. The hook 33 is adapted to engage the cam 40 and the finger 39 is adapted to engage the cam 41.

When the magnet 20 is deenergized, the armature 25 will drop, releasing the hook 30 33 from the cam 40 and permitting the hook 39 to ride out of engagement with the cam 41 on account of the downward pressure the link 27 imparts to the arm 42 of the lever 38. The switch blades are 35 immediately thrown backward, caused by the tension of the spring 43. The lower ends of the pairs of blades engage the lugs or terminals 44 which are connected to a storage battery or any auxiliary source of power 40 supply available. The bolts 45 and 9 have the same function as the bolts 8 and 19, that is, they serve to guide and keep the terminals 44 into close contact with the blades.

45 The spring mechanism is provided with a spring 43 mounted upon a rod 46. This rod 46 has one end passing through an aperture 49 and a lever 47 connected thereto which is fastened in any suitable manner 50 to the switch blades 1 or 3. The other end of the rod 46 is provided with a collar 48 threading thereon, which serves as a bearing surface for one end of the spring 43. When the switch blades are set in contact 55 with the generator plugs or terminals 18, the lower end of the blade will be pulled upward, carrying the lever 47 with it. The rod 46 will consequently follow and the collar 48 will compress the spring 43. I 60 have provided a protecting bushing 50 which prevents chipping of the insulated mounting 6 about the periphery of the aperture 49.

I have found that the electro-magnet 20 65 is apt to be seriously damaged if the switch

is not immediately reset upon the return of normal voltage in the main circuit. When the switch is in normal set position, the armature 25 is attracted to the magnet 20 whereby the inductance is increased sufficiently to prevent overheating or burning out of the magnet. Such damage would result in the burning out of the magnet winding or dangerous overheating of the same, not to mention the waste of current involved. To overcome these objections I 70 automatically control the electro-magnet circuit by providing a pair of terminals 51 connected in the electro-magnet circuit and connected to any one of the phases or feed 80 wires leading from the main source of supply. Mounted on the switch blade is the contact lug 52 adapted to be interposed between and to contact with the terminals 51. This will reduce danger of damage to the 85 electro-magnet which would probably result if the current were permitted to flow continuously through the same when not properly set.

Sometimes through the negligence of the 90 operator, the switch blades are left feeding on the auxiliary power supply too long, which often results in damage to the system on account of the limited supply of power in the auxiliary power supply, such 95 as has been the experience with storage batteries. To warn, in time, the attendant in charge, I provide an alarm mechanism.

This alarm mechanism comprises a pair 100 of terminals 55 bridged across the auxiliary power supply and engages the lug 56 mounted upon the switch blade 2 in any suitable manner. These terminals 55 are connected to an electric bell 57 which will 105 operate as soon as the switch is connected to the auxiliary power supply.

During the period in which said switch blades are in engagement with the auxiliary terminals 44, the armature 25 of the electro-magnet drops down upon the end of the 110 link 38 causing the fingers 39 to swing upwardly and at the same time the link 28 pulls the arm 31 upwardly and swings the hook 33 downwardly. When the switch blades are re-set, the cam 31 engages the 115 finger 39, causing it to swing downward to normal position and hence, return the armature to a point within the range of attraction of the magnet 20, so that it will be held attracted when the voltage is on the 120 line. The hook 33 is permitted to raise so as to engage the cam and notch 40. Thus, it will be seen that the actuation of the link 38 by the cam 41 during resetting movement will permit the lever 31 to be 125 returned to its former position. At the same time, the raising of the armature tests the magnet for voltage on the line. If the voltage has not returned, the armature drops and releases the hook 33.

While I have shown a particular embodiment of my invention, I do not intend to be limited to the details of construction shown or described, but intend that all such 5 modifications and variations as will suggest themselves to one skilled in the art and coming within the spirit of my invention, be included within the terms of the following claims.

10 I claim:

1. In combination with an electric switch having a switch blade member pivotally mounted upon a stationary terminal member and a coöperating stationary terminal member, latching mechanism for holding the blade into engagement with the coöperating stationary terminal member, said latching mechanism comprising a lever arm having a hook at the outer end thereof for 15 coöperating with a shoulder on the blade member, and a second lever arm for resetting the first said lever arm.

2. In combination, a switch blade member, a terminal member for pivotally carrying said blade member, a second terminal member adapted to be normally engaged by one extremity of said blade member, an auxiliary terminal member, the opposite extremity of said switch blade member being 25 adapted abnormally to engage with said auxiliary terminal member, spring mechanism tending to throw the blade member into contact with said auxiliary terminal member and latching mechanism for maintaining the engagement of the switch blade member with said second terminal member and adapted to be electrically released upon failure of voltage, and a voltage controlled electromagnet governing said latching mechanism.

3. In combination, a plurality of stationary terminals, a plurality of switch blades pivoted on said terminals, an electromagnet, a plurality of secondary terminals, a plurality of auxiliary terminals, means for retaining the switch blades in contact with said secondary terminals during the energization of said electromagnet, means for retaining the switch blades in contact with 45 said auxiliary terminals during the deenergization of the electromagnet, said means comprising a lever pivotally connected near the lower extremity of the blade and a rod under spring restraining means connected to the other end of said lever.

4. The combination of a main terminal, an auxiliary terminal, a switch blade pivoted between said terminals, an electromagnet, latching mechanism having operative 50 connection with said electromagnet, said mechanism comprising a plurality of levers adapted to restrain said switch blade from an outward movement, and alarm means comprising jaw contacts adapted to be engaged by a contact lug on said blade.

5. In combination with an electric switch, a main set of contacts, a set of auxiliary contacts, a set of switch blades, an electromagnet connected in the circuit under certain electric conditions and adapted to control the engagement of said switch blades with either set of terminals, latching mechanism interposed between said electromagnet and one set of said contacts, and means for throwing the electromagnet out of the 70 circuit upon release of said latching mechanism.

6. An automatic switch comprising a pair of terminals, a second pair of terminals, a switch blade pivoted on said second pair of terminals, a pair of auxiliary terminals, latching means for holding said first pair of terminals into engagement with said switch blade, an electromagnet for tripping said latch means, whereupon the switch 80 blades are thrown into engagement with the auxiliary terminals, and spring means for retaining said switch blade in contact with said auxiliary terminals.

7. The combination of an electrical switch 90 having a plurality of contacts and switch blades engaging said contacts, means for automatically actuating said switch, said means comprising an electromagnet having operative connection with a pair of levers, 95 the outer ends of which engage said switch blades, and independent means for throwing said electromagnet out of the circuit upon energization.

8. The combination of an electrical switch 100 having a plurality of contacts and switch blades engaging said contacts and adapted to close a main circuit, means for automatically actuating said switch and connected to said main circuit, and interrupting means 105 for automatically disconnecting said first means after the switch blades have been actuated.

9. The combination of an electrical switch 110 having a plurality of contacts and switch blades engaging said contacts and adapted to close a main circuit, means for automatically actuating said switch and connected to said main circuit, interrupting means for automatically disconnecting said first means 115 after the switch blades have been actuated, and an independent circuit adapted to signal the actuation of said switch blades.

10. In a switch, a pair of blades of elbow form, a stationary pivotal contact, said blades being pivoted at their central portion on said contact, a pair of stationary contacts for making contact with the extremities of said blades, said blades lying upon the outside of both the former and the latter contacts and spring means for laterally pressing the blades against the sides of both 120 said contacts.

11. In combination, primary terminals pivotally carrying a switch blade member,

- secondary terminals adapted to be engaged by one extremity of the switch blade member, auxiliary terminals adapted to be engaged by the opposite extremity of the 5 switch blade member, means restraining said secondary terminal engagement and means holding the auxiliary terminals into engagement with the switch blade member, said last means comprising an arm pivoted 10 to the blade member at a point substantially below its pivotal connection, said arm being connected with a rod having an abutment at its outer end and a spring confined on said rod between the abutment and said arm.
- 15 12. In combination, a base, a plurality of terminal contacts carried on said base, a switch member of elbow form pivotally carried between its extremities by the central terminal contact, latching means located 20 substantially above the upper terminal contact, said latching mechanism comprising a lever having a hooked end, the other end of which passes through said base and has operative connection with an armature of 25 an electromagnet, said hooked end adapted to engage said blade members for holding it into engagement with the upper terminal contacts, and spring means for restraining said engagement.
- 30 13. In combination, a base, a plurality of terminal contacts carried on said base, a switch blade member pivotally carried between its extremities by the central terminal contact, latching mechanism substantially 35 above the upper terminal contact, said latching mechanism projecting through said base and having operative connection with an electromagnet, means on the opposite end of the 40 latching mechanism for holding the switch blade member into engagement with the upper terminal, spring means restraining said engagement and tending to engage said switch blade member with the lower contact, an auxiliary contact lug on said switch blade 45 member adapted to disengage a coöperating contact member upon releasing of the latching mechanism, whereupon said electromagnet is thrown out of the circuit.
- 50 14. In combination, a base, a plurality of terminal contacts carried on said base, a switch blade member of elbow form pivotally carried between its extremities by the central terminal contacts, latching mechanism located substantially above the upper 55 terminal contact, said latching mechanism projecting through said base and having operative connection with an electromagnet, means on the opposite end of the latching mechanism for holding the switch blade 60 member into engagement with the upper terminal member, means substantially between the central and lower terminal contacts for restraining said engagement, said means comprising an arm member pivoted 65 to the switch blade member and having
- pivotal connection at its other end with a projecting member, said projecting member passing through said base and having an element at its opposite end serving as an abutment for a spring confined on the projecting member. 70
15. In combination, a base, a plurality of terminal contacts carried on said base, a switch blade member pivotally carried on one of said terminal contacts, latching mechanism substantially above said terminal contacts, said latching mechanism projecting through said base and having operative connection with an armature of an electromagnet, hook means on the opposite end of the 75 latching mechanism for holding the switch blade member into engagement with the free terminal contact under restraining action, and contact means for disconnecting said electromagnet from the circuit upon actua- 80 tion thereof.
16. In combination, an insulated base member, a blade member pivoted on one side of said base and adapted to be connected in series in a main circuit, terminal members carried by said base for coöperating with said blade member, an electro-magnet carried on the opposite side of said base, a latch member controlled by the electro-magnet, said latch member projecting through the 85 base, and an independent terminal member carried by the base and being controlled by the blade member to connect said electro-magnet across the main circuit when the switch blade is closed. 90
17. In combination, a switch having a switch blade adapted to be connected in a line, means tending to throw the switch blade to open position, a latch for holding the blade in closed position, a voltage controlled magnet having a movable magnetic member which controls the latch, said magnet being bridged across the line in which the switch is connected, a separate switch contact for the circuit of the magnet said 100 contact being operated by the switch to disconnect the magnet when the switch is opened.
18. In combination, a switch having a switch blade adapted to be connected in a line, means tending to throw the switch blade to open position, a latch for holding the blade in closed position, a voltage controlled magnet having a movable magnetic member which controls the latch, said magnet being bridged across the line in which the switch is connected, and testing means controlled by the closing of the switch to test the magnet for voltage on the line before the latch becomes operative. 115
19. In combination, a switch having a switch blade, means tending to throw the switch blade to open position, a latch for holding the blade in closed position, a voltage controlled magnet having a movable 120
- 125

magnetic member which controls the latch, said magnet being bridged across the line in which the switch is connected, and means governed by the closing of the switch to 5 raise the magnetic member momentarily into position to be attracted by the magnet before the latch becomes operative, said means being adapted to permit the magnetic member to fall away and release the latch if no voltage 10 is on the line.

20. In combination, a switch having a switch blade, means tending to throw the switch blade to open position, a latch for holding the blade in closed position, a voltage controlled magnet having a movable 15 magnetic member which controls the latch, said magnet being bridged across the line in which the switch is connected, and testing means comprising a cam member for moving 20 the magnetic member into the range of action of the magnet momentarily only when the switch is moved to closed position and before the latch becomes operative to make a momentary test for the present voltage on 25 the line.

21. In combination, a switch having a switch blade, means tending to throw the switch blade to open position, a latch for

holding the blade in closed position, a voltage controlled magnet having a movable 30 magnetic member which controls the latch, said magnet being bridged across the line in which the switch is connected, and testing means for moving the magnetic member within the range of the magnet before the 35 latch becomes operative said means permitting the magnetic member to move away from the magnet if the voltage is off the line, before the latch becomes operative.

22. In a switch, a switch blade, a latch for 40 holding the blade in closed position, a shoulder on the blade for engagement by the latch, a voltage controlled magnet having a magnetic member adapted when no voltage is on the line to move away from the magnet 45 and thereby release the latch from the shoulder, a finger mechanism for lifting the magnetic member into range of the magnet, and a cam member on the blade for engaging the finger to first lift and then release the magnetic member before the latch comes into 50 register with the shoulder.

In witness whereof, I hereunto subscribe my name this 1st day of Aug., A. D. 1918.

ERNEST H. JACOBS.
